UNITED STATES PATENT OFFICE

157,242

DICTATING MACHINE CABINET

Anthony C. De Napoli, Jr., Windsor, Conn., and Raymond Spilman, Yonkers, N. Y., assignors to The Soundscriber Corporation, New Haven, Conn., a corporation of Connecticut

Application August 26, 1949, Serial No. 4,702

Term of patent 14 years

(Cl. D26—14)

To all whom it may concern:

Be it known that we, Anthony C. De Napoli, Jr., and Raymond Spilman, citizens of the United States, residing at Windsor, Connecticut, and Yonkers, New York, respectively, have invented a new, original, and ornamental Design for Dictating Machine Cabinet, of which the following is a specification, reference being had to the accompanying drawing, forming part thereof.

Fig. 1 is a front view of the dictating machine cabinet, showing our new design.

Fig. 2 is a side view of the same.

Fig. 3 is a top view of the same.

We claim:

The ornamental design for a dictating machine cabinet, as shown.

ANTHONY C. DE NAPOLI, JR.
RAYMOND SPILMAN.
